UNITED STATES PATENT OFFICE

148,167

DESIGN FOR A MEDAL OR SIMILAR ARTICLE

Thomas H. Jones, Washington, D. C., and Arthur E. Du Bois, Newark, N. J., assignors to the United States of America, as represented by the Secretary of War

Application January 3, 1947, Serial No. 135,911

Term of patent 14 years

(Cl. D29—19)

To all whom it may concern:

Be it known that we, Thomas H. Jones and Arthur E. Du Bois, citizens of the United States and residents of the city of Washington, in the District of Columbia, and city of Newark, in the County of Essex and State of New Jersey, respectively, have invented a new, original and ornamental Design for a Medal or Similar Article, of which the following is a specification, reference being had to the accompanying drawings, forming a part thereof.

Fig. 1 is a front view of a medal showing our new design.

Fig. 2 is a rear view of the same.

Fig. 3 is a side view of the same.

The essential features of our design are shown in full lines.

We claim:

The ornamental design for a medal or similar article, as shown and described.

THOMAS H. JONES.
ARTHUR E. DU BOIS.
